UNITED STATES PATENT OFFICE.

HENRY STILES, OF MILES, OHIO, ASSIGNOR OF ONE-HALF TO WILL S. REED, OF CLEVELAND, OHIO.

HINGE.

No. 830,022.

Specification of Letters Patent.

Patented Sept. 4, 1906.

Application filed March 16, 1904. Serial No. 198,327.

To all whom it may concern:

Be it known that I, HENRY STILES, a citizen of the United States, residing at Miles, county of Cuyahoga, and State of Ohio, have 5 invented a new and useful Improvement in Hinges, of which the following is a specification, the principle of the invention being herein explained and the best mode in which I have contemplated applying that principle, 10 so as to distinguish it from other inventions.

My invention relates to hinges, and particularly to such hinges as may be applied to doors and screens and which are adapted to swing the latter into their normal closed position and retain them in such position when they have been opened and let loose.

It has for its object the construction of a hinge which shall operate the screen or door, as above stated, by the force of gravity.

20 The annexed drawings and the following description set forth in detail certain means embodying the invention, such disclosed means comprising but one of various mechanical forms in which the principle of the 25 invention may be used.

In said annexed drawings, Figure 1 represents a general elevation of a door and casing, showing my invention as applied thereto. Fig. 2 represents a plan view of one of 30 the members of my improved hinge. Fig. 3 represents a front elevation of the whole hinge. Fig. 4 represents a side elevation of the second member of the hinge. Fig. 5 represents a modification of my invention applied to a door and casing and adapted to allow 35 the door to be swung both in and out. Fig. 6 represents a front elevation of one of the members of said modified hinge. Fig. 7 represents a front elevation of the second member 40 of said modification, and Fig. 8 represents a side elevation of both members of such modified hinge when assembled.

My improved hinge consists of two members C and D, each of which is adapted to be 45 fastened by any approved means to a door or casing. In the construction shown the member C is fastened to the door B and the member D fastened to the casing A. Each of 50 said members is fastened to the door or casing by means of small ears c d, joined to the members C D by any suitable means, but preferably cast integral with the same, as shown. The member C embodies a tubular portion, upon the inner periphery of which is

provided a pin or lug c', projecting inwardly, 55 as shown, toward the center of the portion. The other member D comprises a stud furnished in its upper lateral portion with a vertical groove d', extending downwardly a short distance and terminating in a helical 60 groove d², running downwardly around the stud, as shown in Figs. 3 and 4. Assuming that the member C is fastened to the door B and the member D fastened to the casing A and the door removed from the casing, the 65 pin c' is so positioned in the tubular portion that when the two members of the hinge are assembled the pin c' is adapted to contact the vertical groove d' when the door is swung wide open and then slides to the bottom of 70 the same, whereby the door is held to the casing. Upon releasing the door from the hand the pin c' commences to travel in the helical groove d² and the door is gradually 75 swung shut by the force of gravity, the door 80 shutting without any impetus being given to it in order to start it and swinging gently, so that it does not close with an injurious bang, and neither does it swing back and forth after it has once closed.

In the modified form of my invention illustrated in Figs. 5, 6, 7, and 8 the stud of the member D is provided with two vertical grooves d' d' and with two helical grooves d² and d³, running in directions transversely of 85 each other, as shown in Fig. 7, and communicating at their upper portions with the grooves d' d', these grooves d² and d³ communicating with and terminating within each other at their lowest portions d⁴. By thus 90 providing two helical grooves and two vertical grooves the door may be swung both in and out and may be inserted on the casing upon either side of the same. However, if it is desired one of the vertical grooves d' may 95 be dispensed with, in which case the door could be hung upon the casing from one side only of the latter, but would be enabled still to swing both in and out by means of the two helical grooves. The operation of the pin c' within the grooves d' d', d², and d³ is the same as that of the pin in the grooves d' and d² of the device illustrated in Figs. 1 to 4, the normal position of the door being a closed one and the pin c' lying normally at the lowest 105 portion d⁴ of the grooves d² and d³. When it is desired to open the door, it may be pushed or pulled in either direction, and when re-

leased will return by the force of gravity to its normal closed position in the manner above described. By thus providing the door with a hinge which is adapted to close it by the 5 force of gravity the necessity of providing the door with a lock or other fastening to keep it closed is obviated. The door will always be shut, because it cannot of itself remain in any other position. It will not bang 10 when closing and will not swing back and forth by reason of the wind or other causes. Any number of hinges may be applied to a door, there being two applied in the construction illustrated.

15 It will be seen that the elements common to either form of my hinge above described are a set of communicating grooves in one member of the hinge, of which grooves at least one is helically disposed, and a projecting pin in the other member of the hinge, such pin being adapted to register in such 20 set of grooves. Such set of grooves may comprise, as shown in Figs. 1 to 4, inclusive, a single vertical and a single helical groove or, as shown in Figs. 5 to 8, inclusive, two 25 vertical and two helical grooves, and while but a single set of grooves with a single pin registering therein is shown in the figures referred to and in the accompanying description 30 matter a plurality of such sets might be advantageously employed on a hinge of large size.

Other modes of applying the principle of my invention may be employed instead of 35 the ones explained, change being made as regards the means herein disclosed provided the means stated by any one of the following claims or the equivalent of such stated means be employed.

40 I therefore particularly point out and distinctly claim as my invention—

1. A hinge, comprising the combination of two members, one of said members consist-

ing of a cylindrical stud, the other of said members consisting of a tubular portion 45 adapted to fit over said stud and turn thereon, one of said members being provided in its bearing-surface with a set of communicating vertical and helical grooves, the other with a projecting pin adapted to engage such set of 50 vertical and helical grooves.

2. A hinge, comprising the combination of two members, one of the same consisting of a stud provided with communicating vertical and helical grooves, and the other member 55 consisting of a tubular portion provided with a pin adapted to slide in said vertical grooves to secure the two members together, and adapted to travel in said helical grooves to permit said second member to turn relatively 60 to said first member.

3. A hinge comprising the combination of two members, one of the same consisting of a stud provided with two vertical grooves in its upper lateral surface, two helical grooves in 65 its lower lateral surface, the latter grooves running transversely of, and communicating with each other, each of said helical grooves also communicating with one of said vertical grooves, respectively, and an integral ear for 70 securing such stud to a casing; the other of said members comprising a tubular portion provided with a pin adapted to engage said grooves, and an integral ear for securing such portion to a door, the construction being such that the pin of said tubular portion is adapted 75 to slide in said vertical grooves to secure the door to the casing, and adapted to travel in said helical grooves to allow the door to be swung in either direction, and to allow the 80 door to close by the force of gravity.

Signed by me this 14th day of March, 1904.
HENRY STILES.
